UNITED STATES PATENT OFFICE.

HERMANN ARTHUR KLEMM, OF HARRISON, NEW YORK; ASSIGNOR TO UNION SPECIAL MACHINE COMPANY, OF CHICAGO, ILLINOIS, A CORPORATION OF ILLINOIS.

SEWING MACHINE.

Application filed June 10, 1921. Serial No. 476,395.

To all whom it may concern:

Be it known that I, HERMANN ARTHUR KLEMM, a citizen of the United States, residing at Harrison, in the county of Westchester and State of New York, have invented an Improvement in Sewing Machines, of which the following is a specification.

My present invention relates to a sewing machine and more particularly to the feed mechanism of an overseam sewing machine adapted particularly for use in the sewing operation necessary in connection with so-called full fashioned stockings, slippers, selvage fabrics and various other articles having cut edges. The invention relates particularly to the construction of the feed devices. I am aware that heretofore in sewing machines of this type feed cups have been employed and it has been customary to actuate one of these feed cups positively to drive the other feed cup therefrom either through the fabric which is being operated upon or from the mechanism for positively actuating the positively driven feed cup. The object of my present invention is to provide a feed mechanism of this general type in which both feed cups are positively driven and one feed cup at least is constructed to contain the mechanism for positively imparting thereto an intermittent revoluble movement so that the feed cups are both positively and independently driven in order to operate in the sewing operation in a differential manner. Furthermore, the mechanism employed for driving the feed cups consists entirely of an eccentric, shafts, and series of levers which are adjustable to vary the extent of the feed of both feed cups simultaneously or independently of each other, as will be hereinafter more particularly described.

In the drawing:

Fig. 1 is a side elevation of a sewing machine embodying the mechanism comprising my present invention.

Fig. 2 is a plan view of the same.

Fig. 3 is an inverted plan view.

Fig. 4 is a sectional elevation illustrating more or less diagrammatically the

mechanism for operating the sewing machine needle.

Fig. 5 is also a sectional elevation illustrating the mechanism for operating the looper, and

Fig. 6 is a section through one of the feed cups showing the mechanism by which the same is driven.

Referring to the drawing, the machine as illustrated as embodying my present invention comprises a base 10 and a frame 11 mounted thereon, together with a power or drive shaft 12 journaled in suitable bearings 13, 14 connected to the frame in any desired manner. The drive shaft 12 is fitted with fly wheels 15 with which there are associated belt pulleys 16 in the customary manner for turning the drive shaft.

The forward portion of the base and frame is provided with an extension 17 extending through which is a shaft 18 journaled in bearings 19 connected to or forming part of the front frame extension 17. On the shaft 18 there is a collar 20 which carries an arm 21 extending upwardly and provided with a curved portion 22 terminating in a head 23 so as to form an overhanging arm in which in the head 23 there is journaled a spindle 24 for supporting a feed cup 25. Mounted on the shaft 18 within the forward extension of the base and frame there are collars 26 to which there is connected a yoke 27. Extending from this yoke 27 is an arm 28 for maintaining the yoke, together with the shaft 18 and the collar 20 with the arm 21, in a predetermined position relatively to the frame, this being accomplished by the use of a spring 29, one end of which is connected to the arm 28 and the other end is suitably connected in the frame of the machine, it being understood that by suitable set screws or otherwise the collars 26 are fixed to the shaft 18 as is also the collar 20. By this construction the arm is yieldingly maintained in a normal position, bearing against a stop plate 30 suitably attached to the face of the machine.

I also employ a spindle 31 mounted in a suitable bearing in the forward extension of the base of the machine passing through

the yoke 27 and also through a sleeve 32 for supporting and carrying the second feed cup 33. This spindle 31 and the feed cup are positively driven by a mechanism 5 which will be hereinafter described.

In the machine there is also a vertical rocker shaft 34 which is journaled in bearings 35 and 36 which are carried by brackets 37 and 38 or otherwise and suitably secured 10 in their proper positions in the frame of the machine. On the drive shaft there is an eccentric 39 fitted with a strap 40 and an eccentric rod 41 which extends through an opening provided therefor in the front 15 portion of the frame of the machine. At the forward end of the rod 41 and exteriorly of the machine frame, the same is provided with bearings 42, adapted to receive the round head 43 of a pin 44, the opposite 20 end of which may be adjustably secured in a slot 45 provided for this purpose in an arm 46 which extends from a collar 47 secured on the rocker shaft 34 by a set screw 48 or otherwise.

25 Adjacent the upper end of the rocker shaft 34 there is a collar 49 carrying an arm 50 in which there is a slot 51. The collar 49 is secured in position on the rocker shaft 34 by means of set screws 52 or otherwise.

30 Adjustable in the slot 51 of the arm 50 there is a pin 53. This, as will be understood, may be secured in any desired position in the slot and is provided with a round head 54 which is journaled in bearings 55 connected at one end of a bracket 56. In the bracket 56 one end of a link 57 is adjustably connected, while the opposite end of the link 57 is similarly connected in a bracket 58 which is also provided with bearings indicated at 59. In the bearing 59 there is journaled a round head 60 of a pin 61, the opposite end of the pin 61 being suitably connected in an arm 62 carried by a horizontally disposed rocker shaft 63. The 45 rocker shaft 63 is journaled in bearings 64 and 65 which are integral with or suitably connected to the upper or round portion of the arm 21. At the end of the rocker shaft 63 opposite that carrying the arm 62 there 50 is a collar 66 extending from which is an arm 67 having a round head 68 at its extremity. This rounded head 68 is journaled in bearings 69 connected to a bracket 70. A link 71 is adjustably connected to the bracket 70 and also to a bracket 72. The bracket 72 like the bracket 70 is fitted with bearings 73 in which the round head 74 of a pin 75 is journaled. The opposite end of the pin 75 is fixed in the arm 76 of a bell crank lever that is pivotally mounted at 77 in a bracket 78 carried by the arm 21, the other arm of the bell crank lever being indicated at 79. One end of a pin 80 is connected to the arm 79 of the bell crank lever 60 and journaled on this pin 80 is a bearing 81

carrying a bracket 82. This bracket 82 is adjustably connected by a link 83 to a bracket 84 carrying bearings 85 in which there is journaled a round head 86 at the extremity of an arm 87 by which the feed 70 cup 25 is actuated.

Referring particularly to Fig. 6, it will be seen that the feed cup 25 includes a drum or cylindrical shell 88 within which there is an oscillating member 89 mounted on the 75 spindle 24 by a hub 90. On the oscillating member 89 there are lugs 91 and 92 and the hub 90 is provided with a lug 93 intermediate of the lugs 91 and 92. The outer 80 faces of the lugs 91, 92 and 93 are eccentric to the inner surface of the drum 88 so as to provide wedge-shaped recesses 94, 95 and 96 respectively between the faces of these lugs and the inner surface of the drum 88. Within these recesses I employ balls indicated 85 respectively at 97, 98 and 99, and associated with each ball and lying within the same recess is a spring 100 which at one end bears against the corresponding ball and at the other end is maintained within the recess by 90 a plate 101 or otherwise, the plates 101 being suitably secured in position to the lugs with which they are associated in order to maintain the balls in contact with the inner surface of the drum and the faces of the 95 lugs. Also, as is indicated in Figs. 1 and 2 of the drawing, the feed cup may be provided with a rib at its upper surface, having a knurled face 102 to engage with the material to be sewn in the use of the machine. The arm 87 is suitably connected to the oscillating member 89 and by this means, as will be understood, as the arm 87 is oscillated by the bell crank lever through its connection therewith, as hereinbefore described, the balls 97, 98 and 99 in the forward movement will wedge against the faces of the lugs and the inner surface of the drum and revolve the drum a predetermined portion of a revolution, and in the return 105 movement the drum will remain stationary and the balls permitted to slide along the surfaces of the lugs and the inner surface of the drum.

110 Adjacent the lower end of the rocker shaft 34 there is fixed a collar 103. Extending from the collar 103 is an arm 104 in which there is a slot 105 adapted to receive one end of a pin 106 at the opposite end of which there is a round head 107 journaled in bearings 108. The bearings 108 are carried by a bracket 109 in which one end of a link or rod 110 is adjustably connected, the opposite end of the link 110 being similarly connected in a bracket 111 carrying 115 bearings 112 in which is journaled the round head 113 of an arm 114 which operates an oscillating member to actuate the spindle 31 and the feed cup 33 by the same type of mechanism and in the same manner as the 120 110

125 130

feed cup 25 is actuated, as hereinbefore described, except, as will be understood, the feed cup 33 is driven in the opposite direction—that is to say, assuming the feed cup 25 is driven in a counter clockwise direction as viewed in Fig. 2, the feed cup 33 is driven in a clockwise direction.

As hereinbefore stated, the present invention relates particularly to the devices for operating the feed cups, and the mechanism for operating the needle, as well as operating the looper form no particular part of the present invention, and, for example, may be the same or similar to the same devices as shown and described in Letters Patent No. 571,125, granted to me November 10, 1896. As illustrated in Fig. 4, for example, the needle operating devices may consist of a cam 115 fixed on the drive shaft and adapted to operate within a yoke 116 in order to reciprocate the same and the head thereof 117 which is connected to the needle shaft 118 by a set screw 119 or otherwise. The needle shaft, as illustrated in this figure, is provided with a needle holder 120 in which there is secured a needle 121. These devices, however, form no part of my present invention and are merely illustrative of a manner in which the needle may be driven. Also, for example, the looper mechanism may include a looper member 122 carried at the end of a looper bar 123 to which members there is imparted a reciprocating movement, a lateral movement, and also a swinging movement in order to cause the looper to perform its functions. As illustrated these various movements may be imparted to the looper bar by an arm 124 which is connected at one end to a shaft 125 and a cam 126 fixed on the drive shaft and operating within a strap or yoke 127 in the arm 124 to impart a reciprocating movement to the slide bar 128 on which is mounted a carriage 129, the looper arm 123 being pivotally connected to the carriage 129. The lateral movement of the carriage 129 is effected by means of an arm 130 operated by an eccentric 131 on the drive shaft. A bell crank lever 132 is pivotally connected to the arm 124 adjacent the free end thereof, and at the extremity of one arm of the bell crank lever 132 there is a rounded head 133 through which, by means of suitable bearings, the same is pivotally connected to the end of the arm 130. The opposite end of the other arm of the bell crank lever 132 is connected by a link to the carriage 129. The swinging movement of the looper bar is effected through an arm 134 carried by a strap actuated by an eccentric 135 through the toggle members 136, one of which is connected to an arm 137 and the other to an arm 138, the former being an extension of the carriage and the latter connected to the arbor 65 on which the looper arm is mounted, the

pivotal connection between the toggle 136 and the arm 138 being indicated at 139, and the pivotal connection between the other toggle 136 and the bracket 137 being indicated at 140. As hereinbefore stated, however, this particular form of looper mechanism is substantially the same as that disclosed in the patent to which I have hereinbefore referred.

Referring again to the feeder mechanism 75 it will now be understood that the oscillating member 89 is actuated from the bell crank lever 79 through the link 83 and the bell crank lever is operated from the rocker shaft 63 through the arm 67 and the link 71, 80 while the rocker shaft 63 is operated through the arm 62 and the link 57 by the arm 50 and the vertical rocker shaft 34 which in turn is given a rocker movement from the drive shaft through the eccentric 39, eccentric rod 41 and the arm 46 connected to the eccentric rod 41 by the pin 44. Also it will be equally apparent that the rocker arm 114 and the oscillating member actuated thereby to drive the feed cup 33 are operated 90 through the link 110 by the arm 104 from the rocker shaft 34. The position of the pin 44 may be shifted in the slot 45 in the arm 46 to simultaneously adjust the extent of the rocker movement imparted to the rocker 95 shaft 34 and thereby simultaneously adjust the extent of the feed movement imparted to the feed cups, or the position of the link 57 may be adjusted relatively to the brackets 56 and 58 and the position of the pin 53 100 adjusted to place in the slot 51 in the arm 50 to separately adjust and determine the extent of the step by step movement imparted to the feed cup 25 when the rocker shaft 34 has a predetermined movement imparted 105 thereto. In a similar manner the link 110 may be adjusted to position in the brackets 109 and 111, and also the pin 106 adjusted to position in the slot 105 in the arm 104 to separately vary and adjust the extent of 110 the step by step revoluble movement imparted to the feed cup 33 when a predetermined rocker movement is imparted to the rocker shaft 34. Furthermore, that by this construction, as will now be apparent, the feed cups are both positively driven and the mechanism for driving and the frictional devices by which the outer feed cup is driven are self-contained therein and the feed cups may operate differentially irrespective of the 115 thickness of the material which is being operated upon by the machine.

I claim as my invention:

1. In a sewing machine of the class described, a frame, a drive shaft mounted therein, a rocker shaft also mounted in the said frame, an inner feed cup mounted in the frame, an overhanging rocker arm pivotally mounted in the frame, an outer feed cup mounted in the said rocker arm, devices 125

within the outer feed cup for imparting an intermittent revoluble movement thereto, adjustable devices carried by the said rocker arm for actuating the said means and determining the extent of movement thereof, and means for operating the said devices from the said rocker shaft.

2. In a sewing machine of the class described, a frame, a drive shaft mounted therein, a rocker shaft mounted therein, an adjustable means for moving the rocker shaft from the drive shaft to determine the extent of movement of the rocker shaft, an inner feed cup mounted in the said frame, an overhanging rocker arm pivotally mounted in the said frame, an outer feed cup mounted in the said rocker arm, means within the said outer feed cup for imparting an intermittent revoluble movement thereto, and adjustable devices carried by the said rocker arm and actuated by the said rocker shaft for actuating the means within the outer feed cup to operate the same and determine the extent of movement imparted thereto.

3. In a sewing machine of the class described, a frame, a drive shaft mounted therein, a rocker arm mounted in the frame, a feed cup carried by the said rocker arm, devices in the feed cup for imparting an intermittent partial revoluble movement thereto, a rocker shaft mounted in the frame, means for operating the said rocker shaft from the drive shaft, a second rocker shaft mounted on the said rocker arm, means for imparting a rocker movement to the second rocker shaft from the first rocker shaft, and means for operating the said devices for imparting the intermittent revoluble movement to the said feed cup from the said second rocker shaft.

4. In a sewing machine of the class described, a frame, a drive shaft mounted therein, a rocker arm mounted in the frame, a feed cup carried by the said rocker arm, devices in the feed cup for imparting an intermittent partial revoluble movement thereto, a rocker shaft mounted in the frame, means for operating the said rocker shaft from the drive shaft, means for adjusting the extent of the movement imparted to the rocker shaft from the drive shaft, a second rocker shaft mounted on the said rocker arm, means for imparting a rocker movement to the second rocker shaft from the first rocker shaft, means for adjusting the extent of the movement imparted to the second rocker shaft from the first rocker shaft, and means for operating the said devices for imparting an intermittent revoluble movement to the said feed cup from the said second rocker shaft.

5. In a sewing machine of the class described, a frame, a drive shaft mounted therein, a rocker arm mounted in the frame,

a feed cup carried by the said rocker arm, devices in the feed cup for imparting an intermittent partial revoluble movement thereto, a rocker shaft mounted in the frame, means for operating the said rocker shaft from the drive shaft, a second rocker shaft mounted on the said rocker arm, means for imparting a rocker movement to the second rocker shaft, means for operating the said devices for imparting the intermittent revoluble movement to the said feed cup from the said second rocker shaft, a second feed cup, a spindle mounted in the frame and by which the second feed cup is carried, devices for imparting an intermittent partial revoluble movement to the second feed cup, and means actuated by the first aforesaid rocker shaft for actuating the devices for imparting an intermittent partial revoluble movement to the said second feed cup.

6. In a sewing machine of the class described, a frame, a drive shaft mounted therein, a rocker arm mounted in the frame, a feed cup carried by the said rocker arm, devices in the feed cup for imparting an intermittent partial revoluble movement thereto, a rocker shaft mounted in the frame, means for operating the said rocker shaft from the drive shaft, means for adjusting the extent of the movement imparted to the rocker shaft from the drive shaft, a second rocker shaft mounted on the said rocker arm, means for imparting a rocker movement to the second rocker shaft from the first rocker shaft, means for adjusting the extent of the movement imparted to the second rocker shaft from the first rocker shaft, devices operated by the said second rocker shaft for actuating the devices for imparting the intermittent partial revoluble movement to the said feed cup, a second feed cup mounted in said frame, means within the second feed cup for imparting an intermittent partial revoluble movement thereto, means for actuating the last aforesaid means from the first aforesaid rocker shaft, and means for adjusting the extent of the movement imparted by the first aforesaid rocker shaft to the said devices for imparting the intermittent partial revoluble movement to the said second feed cup.

7. In a sewing machine of the class described, a frame, a drive shaft mounted in the frame, a rocker arm mounted in the frame and yieldingly held in position therein, a feed cup carried by the said rocker arm, devices in the feed cup for imparting an intermittent partial revoluble movement thereto, a vertical rocker shaft journaled in the said frame, a horizontal rocker shaft journaled in the said rocker arm, means for actuating the vertical rocker shaft from the drive shaft, means for operating the horizontal rocker shaft from the vertical rocker shaft, and means for operating the devices

for imparting the intermittent revoluble movement to the feed cup from the said horizontal rocker shaft.

8. In a sewing machine of the class described, a frame, a drive shaft mounted in the frame, a rocker arm mounted in the frame and yieldingly held in position therein, a feed cup carried by the said rocker arm, devices in the feed cup for imparting an intermittent partial revoluble movement thereto, a vertical rocker shaft journaled in the said frame, a horizontal rocker shaft journaled in the said rocker arm, means for actuating the vertical rocker shaft from the drive shaft, means for operating the horizontal rocker shaft from the vertical rocker shaft, means for operating the devices for imparting the intermittent revoluble movement to the feed cup from the said horizontal rocker shaft, a second feed cup, a shaft mounted in the frame for carrying the second feed cup, devices for imparting an intermittent partial revoluble movement to the second feed cup, and means for operating the last aforesaid devices from the said vertical rocker shaft.

9. In a sewing machine of the class described, a frame, a drive shaft mounted in the frame, a rocker arm mounted in the frame and yieldingly held in position therein, a feed cup carried by the said rocker arm, devices in the feed cup for imparting an intermittent partial revoluble movement thereto, a vertical rocker shaft journaled in the said frame, a horizontal rocker shaft journaled in the said rocker arm, means for actuating the vertical rocker shaft from the drive shaft, means for adjusting the extent of movement imparted to the vertical rocker

shaft from the drive shaft, means for operating the horizontal rocker shaft from the vertical rocker shaft, means for adjusting the extent of the movement imparted to the horizontal rocker shaft from the vertical rocker shaft, and means for operating the devices for imparting the intermittent revoluble movement to the feed cup from the said horizontal rocker shaft.

10. In a sewing machine of the class described, a frame, a drive shaft mounted in the frame, a rocker arm mounted in the frame and yieldingly held in position therein, a feed cup carried by the said rocker arm, devices in the feed cup for imparting an intermittent partial revoluble movement thereto, a vertical rocker shaft journaled in the said frame, a horizontal rocker shaft journaled in the said rocker arm, means for actuating the vertical rocker shaft from the drive shaft, means for adjusting the extent of movement imparted to the vertical rocker shaft from the drive shaft, means for operating the horizontal rocker shaft from the vertical rocker shaft, means for adjusting the extent of the movement imparted to the horizontal rocker shaft from the vertical rocker shaft, means for operating the devices for imparting the intermittent revoluble movement to the feed cup from the said horizontal rocker shaft, a second feed cup, a shaft mounted in the frame for carrying the second feed cup, devices for imparting an intermittent partial revoluble movement to the second feed cup, and means for operating the last aforesaid devices from the said vertical rocker shaft.

Signed by me this 6th day of June, 1921.
HERMANN ARTHUR KLEMM.
